DESIGN FOR A TRAVELING BAG

Benjamin Laufman, Newark, N. J.

Application March 8, 1935, Serial No. 55,789

Term of patent 7 years

To all whom it may concern:

Be it known that I, Benjamin Laufman, a citizen of the United States and a resident of Newark, in the county of Essex and State of New Jersey, have invented a new, original, and ornamental Design for Traveling Bags, of which the following is a specification, reference being had to the accompanying drawing forming part thereof.

Figure 1 is a top plan view of a traveling bag showing my new design.

Fig. 2 is a side elevation thereof, and

Figures 3 and 4 are end elevations of the opposite ends of the bag, respectively.

The dominant features of the design are the

approximately trapezoidal contour of the ends of the bag with curved sides, the smaller flat approximately trapezoidal portions inclined inwardly at the lower parts of the ends of the bag, the inverted triangular portions at the top central parts of the ends, and the peculiar folds extending upwardly from the upper corners of the small flat trapezoidal portions. The heavy dotted lines at the ends of the bag represent stitching.

I claim:

The ornamental design for a traveling bag, as shown and described.

BENJAMIN LAUFMAN.
